US00D473273S

(12) **United States Design Patent** (10) Patent No.: **US D473,273 S**
Crawford et al. (45) Date of Patent: **** Apr. 15, 2003**

(54) **EXERCISE BICYCLE HANDLEBAR**

(75) Inventors: **Douglas A. Crawford**, Lafayette, CO (US); **William A. Baker**, Longmont, CO (US)

(73) Assignee: **Nautilus, Inc.**, Louisville, CO (US)

(**) Term: **14 Years**

(21) Appl. No.: **29/156,767**

(22) Filed: **Mar. 6, 2002**

(51) LOC (7) Cl. **21-02**

(52) U.S. Cl. **D21/694; D12/178**

(58) Field of Search **D21/663, 664, D21/665, 666, 667, 668, 694, 697; D12/114, 178; 482/57, 64; 74/551.1, 551.2, 551.6**

Primary Examiner—Philip S. Hyder

(74) Attorney, Agent, or Firm—Dorsey & Whitney LLP

(57) **CLAIM**

The ornamental design for an exercise bicycle handlebar, as shown and described.

DESCRIPTION

FIG. 1 is a perspective view of the exercise bicycle handlebar of the present invention;
 FIG. 2 is a front elevation view thereof;
 FIG. 3 is a rear elevation view thereof;
 FIG. 4 is a left elevation view thereof; and,
 FIG. 5 is a top plan view thereof.
 The broken line showing of the exercise bicycle in FIG. 1 is for illustrative purposes only and forms no part of the claimed design.

1 Claim, 3 Drawing Sheets
